WILLIAM V. ROBINSON, OF LANSING, MICHIGAN.

POLISHING OR GRINDING MACHINE.

1,139,728.

Specification of Letters Patent. Patented May 18, 1915.

Application filed August 21, 1914. Serial No. 857,863.

To all whom it may concern:

Be it known that I, WILLIAM V. ROBINSON, a citizen of the United States of America, residing at Lansing, in the county of 5 Ingham and State of Michigan, have invented certain new and useful Improvements in Polishing or Grinding Machines, of which the following is a specification, reference being had therein to the accompanying drawings.

My invention relates to polishing or grinding machines and more particularly to a machine for polishing or grinding rods, shafts or the like.

The invention resides in the provision of means for efficiently and automatically feeding the work to the grinder; in the structure by which the work may be fed longitudinally across the grinder and properly rotated during its longitudinal travel; in the means for automatically effecting a relative movement between the grinder and the work to disengage the work and grinder at opposite limits of travel of the work; in a construction by which shafts, rods or the like of various lengths may be polished or ground; and further the invention resides in certain arrangements, constructions and combinations of parts as will more fully herein- 30 after appear.

In the drawings,—Figure 1 is a side elevation of a device embodying the invention; Fig. 2 is a front elevation; and Figs. 3 and 4 are respectively detail elevation views of two 35 bearings within which work holding members are journaled, the bearings being respectively mounted upon the end portions of a carriage; Fig. 5 is a detail elevation showing how travel of the carriage is actuated by an endless chain; Fig. 6 is a cross section 40 view of the carriage; Fig. 7 is a plan view showing portions of the mechanisms for driving the carriage and for rotating the work; Figs. 8 to 10 inclusive are detail views 45 of the mounting of a sprocket wheel, whereby the same is adapted for adjustment toward another sprocket wheel.

A designates the main frame of the machine and B an auxiliary frame extending 50 laterally of the main frame and having spaced rails C and D forming a track for a carriage E. The latter is provided with a downwardly-extending arm F vertically slotted at G to receive a pin or roller H that

projects laterally from a chain I. This 55 chain passes over spaced sprockets J and K arranged within the frame B, one of these sprockets as K being driven from a shaft L through the medium of bevel gears M and N respectively fixed to the shaft L and the 60 shaft O of the sprocket J.

Positioned above the auxiliary frame B is a grinder or polishing member P that is carried by a suitable frame Q and is driven from a shaft R by means of pulleys S and T 65 and a belt U. The shafts L and R may be driven by any suitable source of power but are preferably actuated by the following drive trains. Thus V is the main driving pulley which is connected by a belt W to a 70 pulley Y on the shaft R. Z is a small pulley on the shaft R which drives a pulley A' on a shaft B'. The latter—through the medium of pulleys C' and D' and the belt D'—drives a shaft F'. G' is a drive train be- 75 tween the shaft F' and the shaft L.

The carriage E is provided with spaced bearings H' H within which are arranged for rotation work-engaging members I' I². The shaft K' or other member to be ground 80 is engaged with the members I' I² and rotated thereby. To the member I² is secured a sprocket L' that meshes with a gear M' splined to a shaft N'. The latter member has its ends journaled in bearings O' P' 85 adjacent opposite ends of the frame B, and this shaft is driven by means of the belt Q' and pulleys R' S' from the shaft L.

In operation of the structure so far described, the shaft K' or other work to be 90 ground is engaged with the members I' and I² and the grinder or polishing member P adjusted to properly engage the work. Upon power being transmitted to the pulley P the grinder or polishing member is 95 rotated through the medium of the drive trains hereinbefore pointed out, and also motion is imparted to the sprocket J from the shaft L. Upon the rotation of the sprocket J the chain I is driven thereby reciprocating the 100 carriage E longitudinally. During this reciprocation the work carried by the members I' and I² is rotated, since as before stated, the shaft N' is driven from the shaft L. During the continued operation of the 105 machine the work therefore will be longitudinally fed back and forth beneath the grinder and at the same time rotated, until

the desired polishing or grinding is effected. By rotating the work as it is fed beneath the grinder or polisher a very uniform grinding or polishing is accomplished.

5 It is very desirable to provide a machine that will be readily adapted to work of various lengths. In the drawings I have illustrated one embodiment of the invention whereby the grinder or polisher may 10 be readily adjusted to take any length of rod, shaft or the like, within the limits of the machine and yet to produce a uniform grinding or polishing of the work throughout its entire length. As shown, the carriage E is provided adjacent opposite ends with trucks a b, the wheels c of which travel upon the rails C and D. The latter have cut-away portions d, and when the wheels c pass into engagement with these cut-away 15 portions, the work is lowered out of engagement with the grinder or polishing member, since the trucks carry the bearings within which the work is mounted. The parts are so proportioned that the work will be lowered out of engagement with the grinder or polishing member when the latter has reached the end of the work and before it would engage the bearing H' or H. To permit shafts, rods or the like of various 20 lengths to be properly mounted in relation to the work, the trucks a b are adjustable toward and from each other. Thus e are side members preferably formed of angle-shaped iron and which serve to connect the trucks. One of the trucks or both the members a b are connected to the angle iron e so as to be adjusted longitudinally thereof as by providing the truck with a clamp f which when loosened, will allow the truck 25 30 35 to be moved longitudinally of the member e but when tightened, will clamp the truck to said members.

With the construction of carriage just described, the travel of the carriage is that required for the maximum length of rod, shaft or the like, within the capacity of the machine. When a shorter length piece of work is to be ground or polished, when the ends of the work are reached, the wheels 50 55 of the trucks will ride into engagement with the cut-away portions and will continue in engagement with the cut-away portions until the carriage is reversed, the cut-away portions of the rails being of sufficient length to permit of this operation.

While various devices for holding the work might be employed, I have illustrated in the drawings a simple and novel work holder to allow the work to be readily engaged and disengaged therefrom. Thus, the member I² not only is rotatably mounted in the bearing H, but also is longitudinally adjustable therein. As shown, the bearing H is formed of spaced members H³ H⁴, and the gear L' is arranged intermediate the mem-

bers H³ H⁴, and is splined to the member I². At the outer end of the member I² is a head A⁴, against which bears a stop A⁵ composed of an arm pivoted at its lower end to a bracket B⁴ on the truck b. C⁴ is a screw 70 passing through an aperture in the member A⁵ and serving to limit the outward movement of this member. By adjusting the screw C⁴ the length of that portion of the member I² that projects inwardly beyond 75 the bearing A² can be regulated. The member I' is also provided with a head D⁴ against which bears the pivoted arm E⁴. This arm, however, is yieldably moved inward by a spring F⁴ and has one end connected to the member D⁴ and the opposite end attached to a bracket G⁴ upon the truck a.

In the structures shown in Figs. 4 and 5 the inner ends of the members I' I² are tapered and squared in cross section so as to engage a hollow shaft or tubing. When a solid shaft or other members are to be operated upon, the inner end of the members I' I² may be suitably shaped to properly engage the work and couple the same thereto.

90 Preferably the sprocket J is mounted so as to be adjusted longitudinally of the member B to allow the chain to be shortened if so desired, when short pieces of work are being ground. Thus as shown in Figs. 7 to 10 inclusive, the sprocket J is mounted upon a stub shaft that is carried by a member A². The latter has a portion B² engaging a bracket C² attached to the member B as by 95 means of bolts D². The member C² is provided with a portion E² spaced from the member B forming a guide therebetween. F² is a projection upon the portion E² adapted to engage a groove G² in the portion B². Carried by the part B² are clamping screws H², and K² are washers adapted to extend over the upper edge of the portion E². Thus by releasing the screws H² the member B² may be adjusted longitudinally 100 upon the member C².

110 While I have illustrated and described one embodiment of the invention, I do not desire to limit my protection to the particular structure illustrated, but consider the invention to be of sufficient scope to embody various modifications.

115 What I claim as my invention is:—

1. The combination with a grinder or 120 polishing member, of means for feeding work longitudinally of said member, means for rotating said work during the longitudinal feeding thereof, and means for shifting the work clear of said member at a predetermined point in the longitudinal movement of the work.

2. The combination with a grinder or 125 polishing member, of means for feeding work longitudinally of said member, means for rotating said work during the longitudinal 130

feeding thereof, and means for shifting the work clear of said member when the end of the work is reached.

3. The combination with a grinder or polishing member, of a work-holder, means for reciprocating said work-holder longitudinally of said member, means for rotating said work during the longitudinal feeding thereof, and means for disengaging the work and said member at spaced points in the longitudinal reciprocation of said holder.

4. The combination with a grinder or polishing member, of a work-holding carriage reciprocating longitudinally of said member, and means for actuating said carriage to move the work carried thereby out of engagement with said member at a predetermined point in the travel of said carriage.

5. The combination with a grinder or polishing member, of a work-holding carriage reciprocating longitudinally of said member, and means for lowering said carriage at a predetermined point in the travel of said carriage to disengage the work from said member.

6. The combination with a grinder or polishing member, of a work-holding carriage, a track upon which said carriage runs, means for reciprocating said carriage longitudinally of said member, said track being provided with a cut-away portion for the purpose described.

7. The combination with a grinder or polishing member, of a work-holding carriage, a track upon which said carriage runs, means for reciprocating said carriage upon said track, the latter being provided with cut-away portions arranged to lower the carriage at opposite ends of its travel so as to disengage the work from said member when said member is in immediate proximity to the ends of the work.

8. The combination with a grinder or polishing member, of a work-holding carriage provided with trucks adjacent opposite ends thereof, a track upon which said trucks travel, provided with a cut-away portion for the purpose described.

9. The combination with a grinder or polishing member, of a work-holding carriage comprising spaced bearings within which the work is mounted for rotation, spaced trucks upon which said bearings are mounted, a track upon which said trucks travel, means for reciprocating said carriage upon said track, and means for rotating said work during the reciprocation of said carriage.

10. The combination with a grinder or polishing member, of a work-holding carriage comprising spaced bearings within which the work is mounted for rotation, spaced trucks upon which said bearings are mounted, a track upon which said trucks travel, means for reciprocating said carriage upon said track, a driven shaft, a gear slid-

able longitudinally on said shaft but secured to rotate therewith, and a pinion on said carriage meshing with said gear and secured to rotate with the work.

11. The combination with a grinder or polishing member, of a work-holder, means for reciprocating said work holder longitudinally of said member, means for disengaging the work and said member at spaced points in the longitudinal reciprocation of said holder, and means for adjusting the work holder for various lengths of work.

12. The combination with a grinder or polishing member, of a work-holding carriage reciprocating longitudinally of said member including work-engaging members, means for adjusting the distance between the work-holding members, and means for actuating said carriage to move the work carried thereby out of engagement with said member at a predetermined point in the travel of said carriage in the different positions of adjustment of said work-holding members.

13. The combination with a grinder or polishing member, of a work-holding carriage reciprocating longitudinally of said member, means for adjusting the length of the carriage, and means for actuating said carriage to move the work carried thereby out of engagement with said member at a predetermined point in the travel of said carriage.

14. The combination with a grinder or polishing member, of a work-holding carriage reciprocating longitudinally of said member, means for lowering said carriage at a predetermined point in the travel of the same to disengage the work from said member, and means for adjusting the length of said carriage.

15. The combination with a grinder or polishing member, of a work-holding carriage reciprocating longitudinally of said member, including spaced trucks, work-holding means carried by said trucks, and means for adjusting the distance between said trucks.

16. The combination with a grinder or polishing member, of a work-holding carriage reciprocating longitudinally of said member, including spaced trucks, work-holding means carried by said trucks, and means for varying the distance between said work-holding means.

17. The combination with a grinder or polishing member, of a work-holding carriage reciprocating longitudinally of said member, including spaced trucks, work-holding members respectively carried by said trucks, means for connecting said trucks together, and means for effecting a relative adjustment between said trucks, for the purpose described.

18. The combination with a grinder or polishing member, of a work-holding car-

riage reciprocating longitudinally of said member, including spaced work-engaging members, bearings in which said members are journaled, means for rotating one of said members, and means for yieldably retaining said members in engagement with the work.

19. The combination with a grinder or polishing member, of a work-holding carriage reciprocating longitudinally of said member, including spaced work-engaging members, bearings in which said members are journaled, means for rotating one of said members, and means for yieldably moving one of said members toward the other.

15 20. The combination with a grinder or polishing member, of means for feeding work longitudinally of said member, means for rotating the work during the longitudinal feeding thereof, and means automati-

cally shifting one end of the work out of its 20 path of travel at a predetermined point in said path, to disengage the work from said member.

21. The combination with a grinder or 25 polishing member, of a work-holding carriage reciprocating longitudinally of said member, means for rotating the work during reciprocation of the carriage, and means for automatically shifting one end of the carriage out of its path of travel at a pre- 30 determined point therein, to disengage the work from said member.

In testimony whereof I affix my signature in presence of two witnesses.

WILLIAM V. ROBINSON.
